HERMANN ALWIN DUTSCHKE, OF CASSEL, GERMANY

INDICATING DEVICE FOR THE POWER CONSUMPTION IN MOTOR CARS AND THE LIKE

Application filed August 2, 1929, Serial No. 383,137, and in Germany June 12, 1929.

This invention relates to a device designed to indicate in H.P. the power consumption of motor cars, flying apparatus, motor boats and similar land-air-and water-vehicles.

5 The driver can read on the indicating device the actual efficiency of the motor.

The apparatus is designed to complete the commonly used indicating devices for indicating the consumption of benzine, or the 10 travelling speed. With the aid of the device, according to the invention, the driver or pilot can always control the accurate efficiency of the vehicle during travel, judge of the quality of the driving fluid, observe sources of error in 15 the driving gear or in the motor, ascertain exceptionally great friction of moving elements, discover unfavourable compression, owing to increase of the efficiency of the motor, find out lost speeds on a measuring 20 apparatus, and generally keep the motor better under control than this was hitherto possible.

The indicating device consists preferably 25 of an indicating plate to be fixed on the dash board and of a hand movable on a scale, the hand being positively connected by a transmission mechanism with a device which is dependent on the action of the motor, so that alterations of the motor efficiency can be read 30 by the indication of the hand. The device for transmitting the movement may be mechanical, electric, hydraulic or pneumatic.

The device which records the changing 35 function or efficiency of the motor may be arranged in the suction conduit, in the exhaust conduit, in the motor or in the compression of the same, or in the driving gear of the vehicle. It forms a kind of dynamometer.

40 The apparatus does not operate when for instance the vehicle is running down an incline without the motor running.

Several embodiments of the invention are shown by way of example in the accompanying drawings in which:

45 Fig. 1 shows diagrammatically an apparatus to be connected to the suction of the motor.

50 Fig. 2 is a similar view, showing an indicating device for the exhaust of the motor working on the same principle.

Fig. 3 shows in elevation an apparatus operated from the driving gear of the motor.

Fig. 4 is a cross section on line 4-4 of Fig. 3.

Fig. 5 shows diagrammatically another 55 form of construction of the apparatus driven from the driving gear.

Referring to Fig. 1 a cylindrical extension *b* on the suction conduit *a* holds a piston *c* hingedly connected by a rod *d* with a lever *e* fulcrumed on a support *f* and controlled by a pull spring *g*, fixed by a nut *g'* in the foot plate of the support *f*. The lever *e* is connected by a Bowden cable *h* with a driving element of a hand *i* adapted to move over a scale *i'* of the indicator *i*. The scale is subdivided in H.P. on the base of certain standards. If the motor, at greater power consumption, sucks more strongly, the piston *c* is more strongly pulled into the extension *b* and pulled back through the intermediary of the lever *e* by the spring *g*, when the motor efficiency increases again.

The changing power consumption of the vehicle is sensitively transmitted upon the piston *c*, lever *e* and spring *g* and thereby also upon the indicating device so that the driver can permanently read on the dash board the efficiency of the vehicle.

The apparatus shown in Fig. 2 has a similar effect, it being however operated from the exhaust pipe *a*, and the lever *e* is mounted so that the rod *d* and the spring *g* act upon one and the same arm of the lever.

Figs. 3 and 4 show the apparatus operated 85 from the driving gear of the vehicle. Between the shafts *q* and *r* a spring-controlled clutch *u* is mounted on pins *v*. The half *s* of the clutch is rigidly connected with the shaft *r* and comprises an inclined plane *w* on which the other clutch half *m* is rotatably mounted. The hub *n* of this clutch half *m* is shiftable on the shaft *q* by guide slot *n'* and pin, but not rotatable, the hub bearing against a spring *o* which bears against a stationary collar *p* of the shaft *q*. The roller *k* of a lever-like feeler *e*, pivotally mounted on a support *f* and controlled by a spring *g*, is running on the clutch element *m*. The lever is connected by a Bowden cable *h* to the indicator *i*.

When the torsion moment between the driving shafts r and q is altered by the spring clutch, the clutch half m is adjusted by the inclined plane x , x on the clutch half s so that the clutch half m yields in compressing the spring o , the feeler e participating in this shifting movement, wherefrom results an alteration of the position of the indicator i .

When the power consumption or efficiency of the motor driving the shaft q changes, the spring o pushes back the clutch half m in rotating the same on the inclined plane x — x .

The transmission upon the indicating device a may be electric, provided a current meter or the like be used as indicating device, the scale of this indicator being gauged in H.P. in accordance with the motor efficiency.

In this case the feeler e may for instance be connected to an adjustable contact z (Fig. 5) guided on a resistance w inserted in the circuit.

For the yieldable clutch between these driving shafts q , r any other clutch of suitable type may be substituted.

I claim:—

An indicating device for power consumers in motor cars and other land, air and water vehicles driven by motors, comprising in combination two shafts, a yielding clutch adapted to couple said two shafts, a clutch half shiftable on one of said shafts, a lever-like feeler adapted to be guided by said shiftable clutch half, a scale on the dash board of the vehicle, a hand movable on said scale, and a Bowden cable adapted to transmit the movement of said feeler to said hand, to indicate the H.P. transmitted by said clutch.

In testimony whereof I affix my signature.
